DOOR APPARATUS AND CONTROL

William T. Litherland, Pontiac, Mich., assignor to General Motors Corporation, Detroit, Mich., a corporation of Delaware

Application August 30, 1955, Serial No. 531,527

2 Claims. (Cl. 268—47)

This invention relates generally to doors and automatic apparatus for opening and closing the doors. The invention refers more particularly to doors of the type that are used on public conveyances, such as railway trains, and is specifically concerned with the doors which connect the main part of the car to the vestibule of the car.

Many controls have been proposed for operating vestibule doors. These controls, however, are complicated and are subject to various defects and deficiencies; for example, many of the doors must be manually opened, other doors require operation of various controls not located near the doors—requiring the person desiring to pass therethrough to hunt for the operating mechanism. Quite often the doors are difficult to open because the controls therefor are subject to frequent failure. Such doors have previously required a substantial amount of maintenance and have been the cause of frequent accidents which in some instances resulted in serious injury.

The present invention has been proposed to provide a door control which is extremely simple to operate, completely safe, and requires the minimum of attention from the standpoint of servicing and repair.

One important object of the invention is to provide a door control which enables the persons using the doors to merely momentarily touch the doors themselves to open them and maintain them open for a predetermined interval after which the doors will automatically close. If, however, any obstruction should remain between the doors as they close, the touching of this obstruction by the doors will immediately cause the doors to again open and again remain open for a predetermined interval.

For further objects and a fuller understanding of this invention reference may be had to the accompanying detailed description and the drawing, in which:

The single figure represents schematically a pair of doors for which the new control is ideally suited, including the door-operating mechanisms and the unique control therefor.

Referring now to the drawing, in the particular example shown, a railway vehicle 2 is provided at one end thereof between the main part of the car and the vestibule with a pair of sliding doors 4 which are suitably hung and guided so as to easily slide apart to provide passage between the vestibule and the main part of the car. Each of these doors adjacent their abutting edges is provided with a so-called sensitive edge 6. Each of the sensitive edges 6 is diagrammatically shown in a small sectional insert as operatively controlling a switch indicated by a numeral 8. It should be emphasized at this point that these sensitive edges are a well-known product readily available on the open market and in and of themselves form no part of this invention and therefore no further description is deemed necessary with respect thereto other than to say that a slight touching, which is easily regulated for more or less sensitivity, will cause either of the switches 8 to close or open, whichever may be desired. The sensitive edges 6 and switches 8, of course, form important

2

elements of the unique door control and their function in the control will be brought out in detail shortly.

Each of the doors is provided with an actuating link 10 which has one end pivotally attached to the door to approximately its vertical midpoint. Each lever 10 is fulcrumed at a point 12 fixed as by bracket 14 to the main structure of the car. The opposite end 16 of the right-hand link 10, as viewed in the drawing, is pivotally fastened at point 18 to an operating rod 20 which is connected to a conventional air servomotor or piston and cylinder assembly 22. The link 10 for the left-hand door, as viewed in the drawing, has its end 16 connected by means of a rod 24 to a small lever 26 pivoted to the main structure of the car at 28 and connected to the end 16 of the right-hand lever 10 by means of a link 30. This latter structure interconnects both the right-hand and left-hand levers 10 so that the doors move uniformly together and apart upon appropriate actuation of the cylinder and piston assembly 22. Air is supplied to the opposite sides 20 of the piston of the servomotor 22 by means of a closing solenoid-operated (air magnet) valve 32 and a solenoid-operated opening (air magnet) valve 34 connected to opposite ends of the cylinder of assembly 22. These air magnet valves regulate the supply of air to the cylinder 25 of assembly 22 from a suitable air pressure source via the piping 36. The extent of opening of the doors is limited by the levers 10 abutting suitable cushioned stops 38 provided on the bulkhead separating the vestibule from the main part of the car.

30 A suitable voltage source such as the battery BAT is provided for operating the electrical portion of the control whose main components include a manually controlled switch SW, a relay 40 having a pair of interlocking switches 42 and 44, a door-control switch 46 having a normally open and a normally closed position, the aforementioned switches 8 operated by the sensitive edges, the solenoid portions of the air valves 32 and 34 and a capacitor 48. The operation of the control is as follows:

40 The switch SW, it will be observed, has two positions as viewed in the drawing, an upper position and a lower position. When the train is in motion the switch SW will normally be placed in its uppermost position for automatic operation of the doors. Assuming the switch SW to be in this position and someone desires to pass between the doors he would place his hand or finger on one of the sensitive edges as directed by a legend placed thereon. The touching of one of the sensitive edges will cause one of the switches 8 to close. Closure, let us say, of the left-hand switch 8 as viewed in the drawing will enable a current to flow from the negative side of the battery through conductors 50 and 52, the now closed left-hand sensitive edge of switch 8, conductors 54, 56, 58 and 60, through the energizing winding 62 of relay 40 and conductor 64 to ground GR. Energization of the winding 62 of relay 40 will cause its interlocks 42 and 44 to move from their normally open position to their closed position, that is, from their uppermost position to their lowermost position. Movement of the interlock 44 to its lowermost position will close a holding circuit for the energizing coil 62 of relay 40. This holding circuit may be traced out as follows: Beginning with the negative side of the battery BAT current will flow through conductor 50, conductor 66, conductor 68, the contacts of the door switch 46 in the position shown when the doors are fully closed or only partially opened, conductor 70, the interlock 44 in its lowermost position and conductors 58 and 60, winding 62 of relay 40, and conductor 64 to ground GR. Because of this holding circuit the winding of the relay 40 will remain energized even though the sensitive edges 6 are no longer being touched and this relay will remain energized until the doors are fully opened. The

door-opening circuit is completed by the upper interlock 42 of the relay 40 moving to its lowermost position as viewed in the drawing so as to energize the door-opening air magnet valve 34. This door-opening circuit includes the negative side of the battery BAT; conductors 50, 66; conductor 72; the right-hand upper contact of the switch SW; conductor 74; the upper interlock of the relay 40 now in its lowermost position; conductors 76, 78; the energizing winding of the door-opening solenoid 34 and to ground GR. Since the relay 40 is held in or picked up, this door-opening solenoid 34 will remain energized and the doors will move to their fully open position. As they do so, however, the door-control switch 46, at the time the doors are fully opened, is moved from its left-hand position as viewed in the drawing out of engagement with the left-hand contact into engagement with the right-hand contact. Movement of switch 46 away from the left-hand contact breaks the holding circuit for the winding 62 of the relay 40. However, because of the presence of the capacitor 48, which is connected in parallel (by means of the conductors 80 and 82) with the winding 62, the relay 40 will remain energized or picked up until this capacitor is discharged, i. e., for a predetermined interval of time. Also, movement of the door-control switch 46 to its right-hand contact as the doors are fully opened closes the door-closing circuit to thereby energize the solenoid-operated valve 32 which supplies air to the cylinder assembly 22 so as to cause the doors to close. This latter circuit may be traced out as follows: Beginning with the negative side of the battery BAT current may flow through conductors 50, 66, 68; the right-hand contact of door-control switch 46; conductor 84; air pressure switch 86 which is closed on proper maintenance of operating pressure in the air pressure source; conductor 88; the left-hand upper contact of the switch SW as viewed in the drawing; conductor 90 and the air magnet valve 32; thence to ground GR.

Since both the opening air magnet valve 34 and the closing air magnet valve 32 are energized at the same time, however, the doors will remain in the fully open position until such time as the capacitor 48 discharges, after which relay 40 will drop out and de-energize the door-opening circuit. The door-closing circuit then is effective to close the doors at which time the door-control switch 46 will return to its left-hand position in contact with its left-hand contact.

Return of the door-control switch to its left-hand contact, as viewed in the drawing, de-energizes the door-closing magnet valve 32 and again sets up the holding circuit for relay 49. This action will be repeated when the sensitive edges are touched either in the fully closed position or the partially open position. If the sensitive edges are leaned against or touched when the doors are fully opened the doors will continue to remain fully open because of constant energization of the winding 62 of the relay 49.

It should also be mentioned that the door is capable of being permanently held open as, for example, when in the station and passengers are continuously passing through the doors either to disembark from the train or board the train. This may be accomplished by moving the switch SW to its lowermost position as shown in the drawing in which case the door-opening solenoid 34 will be permanently energized by current flowing from the negative side of the battery BAT through conductors 50, 66, 72; the right-hand side of switch SW in its lowermost position; conductor 78 and solenoid 34 to ground GR. Actually switch SW in lower position is spring loaded so that when released it returns to a center or "off" position when released. This breaks the complete

door-control circuit and doors will remain in open position. To close doors, place switch SW in upper position. With switch in upper position, doors will close and circuit will be returned to automatic operation.

5 From the foregoing description it may be appreciated
that a door apparatus and control has been provided
which is extremely simple and which utilizes sensitive
edges in a unique way to completely operate the doors
from a fully closed or partially closed position. The use
10 of a capacitor for the purpose of holding the doors open
for a predetermined interval of time is also believed to be
a unique feature of this invention since, formerly, attempts
were made to hold such doors open by complicated door
switches having multiple contacts, etc.

15. What I claim is:

1. An electrical control for a door including a sensitive edge having a switch actuated thereby upon touching and a door-operating linkage comprising first electrical means connected to said linkage operable to open said door, second electrical means connected to said linkage operable to close said door, a voltage source in electrical circuit with said switch and said electrical door-opening means, a relay energizable by touching of said edge to close said switch, a holding circuit for said relay energizable by energization of said relay, a door switch in said holding circuit operable by full opening of said door to break said holding circuit, a capacitor connected to said source in parallel with the winding of said relay to delay dropping out of said relay upon breakage of said holding circuit, said relay including contacts closed by energization thereof in series with contacts on said door switch closable upon full opening of said door to energize said door-closing means whereby said door closes upon discharge of said capacitor.

2. An electrical control for a door including a sensitive edge having a switch actuated thereby upon touching and a door-operating linkage comprising first electrical means connected to said linkage operable to open said door, second electrical means connected to said linkage operable to close said door, a voltage source in electrical circuit with said switch and said electrical door-opening means, a relay energizable by touching of said edge to close said switch, a holding circuit for said relay energizable by energization of said relay, a door switch in said holding circuit operable by full opening of said door to break said holding circuit, a capacitor connected to said source in parallel with the winding of said relay to delay dropping out of said relay upon breakage of said holding circuit, said relay including contacts closed by energization thereof in series with contacts on said door switch closable upon full opening of said door to energize said door-closing means whereby said door closes upon discharge of said capacitor, and manually operated switching means between said voltage source and said first electrical means operable to energize said first electrical means and hold open said door.
